SIGNAL AMPLIFIER

Harold M. Lewis, Allenhurst, N. J., assignor to
 Hazeltine Corporation, a corporation of Delaware

Application October 2, 1941, Serial No. 413,275

11 Claims. (Cl. 179—171)

The present invention relates to signal amplifiers and, particularly, to signal amplifiers adapted to provide a balanced output from an unbalanced input.

It is frequently desirable, especially in the translation of audio-frequency signals, that a signal-translating channel having a balanced input circuit be coupled to a signal-translating channel having an unbalanced output. While such coupling may be effected by a coupling transformer, it is generally more economical and frequently more satisfactory to provide a coupling system comprising a signal amplifier of the phase-inverter type. In one form of prior art amplifier of this nature, two vacuum tubes are used and their output circuits are connected to provide a balanced amplifier output. A signal to be amplified is applied to the input circuit of one of the tubes and a portion of the output of that tube is applied to the input circuit of the other, the applied portion being such that the signals developed in the outputs of the two tubes are approximately equal in magnitude. An arrangement of this nature requires an initial critical proportioning and adjustment of the circuit parameters to provide the desired balanced output, and any subsequent change in the values of the circuit parameters, such, for example, as the act of replacing either one of the amplifier tubes, is very likely to result in substantial unbalance of the output of the amplifier. Moreover, this arrangement has the disadvantage in certain applications that the repeating ratio is fixed at a value equal to twice that of the gain of the particular amplifier tube to which the input signal is applied.

Another form of prior art amplifier of the phase-inverter type comprises a signal amplifier tube having an anode-load impedance and an unby-passed cathode resistor. The desired balanced output of this arrangement is obtained by coupling to the anode and the cathode elements of the amplifier tube. This arrangement does not require quite the critical proportioning of the constants of the circuit parameters used as does the prior art phase inverter previously mentioned, but has the disadvantage that the repeating ratio of the amplifier can never exceed unity. There is the further disadvantage in this arrangement that the cathode of the amplifier tube is maintained above ground potential at signal frequencies, a condition which tends to introduce undesired hum where the amplifier tube is of the indirectly-heated cathode type, due to

leakage between the cathode and its heater element.

It is an object of the present invention, therefore, to provide a new and improved signal amplifier of the type adapted to provide a balanced output from an unbalanced input and one which avoids one or more of the disadvantages and limitations of the prior art devices of this nature.

10 It is an additional object of the invention to provide a signal amplifier of the type described in which the desired balance of output is effected not only without the requirement of critical proportioning and adjustment of the circuit parameters, but remains substantially balanced even though the circuit parameters may change during the operation of the amplifier.

15 It is a further object of the invention to provide a signal amplifier of the phase-inverter type having a new and improved form of gain control, whereby the repeating ratio of the amplifier may be adjusted at will over a wide range of values while at the same time maintaining a high degree of balance of the amplifier output.

20 In accordance with the invention, a signal amplifier comprises a pair of vacuum tubes each having input electrodes and an associated input circuit and output electrodes and an associated output circuit. The output circuits are connected to form a balanced amplifier output circuit. The amplifier includes means for applying to the input circuit of one of the vacuum tubes a signal to be amplified, means for applying to the input circuit of the other of the vacuum tubes a portion of the output of the one vacuum tube, and means for maintaining the output of the amplifier balanced over a range of values of the portion applied to the input circuit of the aforesaid other vacuum tube comprising a relatively high impedance effectively common to all of said input and output circuits, the value of said impedance being such that the product of said value and the mutual conductance of one of said vacuum tubes is a number considerably greater

25 than unity.

30 For a better understanding of the present invention, together with other and further objects thereof, reference is had to the following description taken in connection with the accompanying drawing, and its scope will be pointed out in the appended claims.

35 Referring now to the drawing, Fig. 1 is a circuit diagram, partly schematic, of a complete carrier-signal receiver embodying the invention; Fig. 2 is a simplified circuit diagram of a signal

amplifier embodying the invention and is used as an aid in explaining the operation of the invention; Figs. 3 and 4 are graphs representing certain operating characteristics of a signal amplifier embodying the invention; and Fig. 5 is a circuit diagram representing a modified form of the invention.

Referring now more particularly to Fig. 1, there is represented schematically a complete carrier-signal receiver of a conventional design embodying the present invention in a preferred form. In general, the receiver includes a radio-frequency amplifier 10 having its input circuit connected to an antenna system 11, 12 and having its output circuit connected to an oscillator-modulator 13. Connected in cascade with the oscillator-modulator 13, in the order named, are an intermediate-frequency amplifier 14 of one or more stages, a detector and automatic volume control supply 15, an audio-frequency signal amplifier 16, more fully described hereinafter, an audio-frequency amplifier 17 of one or more stages, and a sound reproducer 18. An automatic amplification control or A. V. C. circuit is connected between the output circuit of the automatic volume control supply of unit 15 and the input circuits of one or more of the tubes of the radio-frequency amplifier 10, the oscillator-modulator 13, and the intermediate-frequency amplifier 14 in conventional manner.

It will be understood that the various units just described may, with the exception of the signal amplifier 16, be of a conventional construction and operation, the details of which are well known in the art, rendering detailed description thereof unnecessary. Considering briefly the operation of the receiver as a whole, and neglecting for the moment the operation of the signal amplifier 16, presently to be described, a desired carrier signal is selected and amplified by the radio-frequency amplifier 10, converted to an intermediate-frequency carrier signal in the oscillator-modulator 13, amplified in the intermediate-frequency amplifier 14, and detected by the detector of unit 15, thereby to derive the audio-frequency modulation components comprising the audio signal. The audio-frequency signal is, in turn, amplified in the audio-frequency amplifier 16, further amplified in the audio-frequency amplifier 17 and is reproduced by the sound reproducer 18 in a conventional manner.

The automatic amplification control or A. V. C. bias derived from the A. V. C. supply of unit 15 is effective to control the amplification of one or more of the units 10, 13 and 14 in accordance with the amplitude of the received carrier signal to maintain the carrier-signal input to the detector of unit 15 within a relatively narrow range for a wide range of received signal intensities.

Referring now more particularly to the portion of the system embodying the present invention, there is coupled to the output of the detector of unit 15 a signal amplifier 16. The amplifier 16 includes a pair of vacuum tubes 19, 20 having input electrodes comprising control grids 21, 22 and cathodes 23, 24, respectively, and having output electrodes comprising anodes 25 and 26, respectively. The input electrodes of vacuum tube 19 have an associated input circuit comprising a grid leak 28, and an unby-passed cathode bias resistor 29. The input electrodes of vacuum tube 20 also have an associated input circuit comprising a grid leak resistor 30 and the cathode resistor 29. The anode 25 of tube 19 has an associated output circuit comprising a load resistor 27

and a source of space current comprising a battery 31. The anode 26 of vacuum tube 20 similarly has an associated output circuit comprising a load resistor 32 and the same source of space current 31. As thus arranged, the load resistors 27 and 32 are connected in series between the anodes 25 and 26 with their junction grounded at signal frequencies through source 31 to form a balanced amplifier output circuit. A balancing impedance comprising a resistor 33 of relatively large value is connected in series with the resistor 29 between the cathodes of vacuum tubes 19 and 20 and ground. The amplifier 16 includes means for applying to the input circuit of one of the vacuum tubes a signal to be amplified, this means comprising a coupling condenser 34 connected between the grid 21 of the vacuum tube 19 and the ungrounded input terminal x' of the amplifier input terminals x x' . There is also included means for applying to the input circuit of the other vacuum tube 20 a portion of the output of the first vacuum tube 19, this means comprising a coupling condenser 35 connected between the grid 22 of vacuum tube 20 and an adjustable tap 36 provided on the load resistor 27 included in the output circuit of vacuum tube 19.

The signal which is applied from the output circuit of the detector of unit 15 to the input terminals x , x' , of the amplifier 16 is applied between the control grid 21 of this tube and ground and thus is applied across the resistors 28 and 33 in series. Similarly, the signal applied from the output circuit of vacuum tube 19 to the input circuit of vacuum tube 20 is applied across the resistors 30 and 33 in series. Now, since the space currents of both of the vacuum tubes 19 and 20 flow through the resistor 33, it will be evident that the resistor 33 is effectively common to the input and output circuits of both of the vacuum tubes 19 and 20.

Considering now the operation of the circuit just described, the signal applied to the input circuit of vacuum tube 19 is repeated by this tube in a conventional manner to develop across the load resistor 27 in the output circuit thereof an amplified signal. A signal potential is also developed across the resistors 29 and 33 by the output current of tube 19, this signal potential being of degenerative phase in the input circuit of vacuum tube 19. The signal potential developed across the resistors 29 and 33 and a portion of that developed across the lower portion of the load resistor 27 below the tap 36 are applied to the input circuit of vacuum tube 20 to develop across the load resistor 32 in the output circuit of this tube an amplified signal potential. Since the space current of vacuum tube 20 also flows through the resistors 29 and 33, the signal potential developed across these resistors by the space current of vacuum tube 20 is of degenerative phase with respect to the input circuit of this tube but is of regenerative phase with respect to the input circuit of vacuum tube 19. For the special case where the tap 36 is so adjusted that the portion of the amplified signal applied from the output of vacuum tube 19 to the input circuit of vacuum tube 20 is just equal to that applied from the detector of unit 15 to the input circuit of vacuum tube 19, the signal potential developed across the resistor 33 by the output current of tube 19 is just equal in magnitude and opposite in phase to that developed across this resistor by the output current of tube 20. Consequently, the two signal potentials developed across the resistor 33 effectively

cancel each other and thus are neither degenerative nor regenerative in the input circuits of tubes 19 and 20. When the tap 36 has any other adjustment, the signal potentials developed across the resistor 33 by the output currents of tubes 19 and 20 tend to maintain this relationship since any difference either in phase or magnitude therebetween results in a degenerative or regenerative effect, as the case may be, in the input circuits of each of the tubes tending to reestablish equality of magnitude and oppositeness of phase between the signal potentials. The resistor 33, which is effectively common to all of the input and output circuits of tubes 19 and 20, has a relatively large value proportioned in a manner presently to be considered in greater detail. It is thus effective by virtue of the large signal potentials developed thereacross to maintain the output of amplifier 16 balanced over a comparatively wide range of values of the portion of the signal output of vacuum tube 19, determined by the setting of the adjustable tap 36 on the load resistor 21, which tap selectively controls the value of the above-mentioned portion of the signal output which is applied to the input circuit of the vacuum tube 20 to control the repeating ratio of amplifier 16.

The more detailed operation of the amplifier 16 will become evident from the following mathematical analysis. The simplified circuit diagram of Fig. 2 corresponds to the amplifier 16 of Fig. 1, corresponding circuit elements being designated by corresponding reference numerals, except that the source of space current 31 is omitted for simplicity, the resistors 29 and 33 are lumped into a common cathode resistor K, and the source of the signals to be amplified is represented simply by an alternating current source e_0 . The selectable portion of the load resistor 21 below the tap 36 is designated as R.

The magnitude of the signal voltage e_1 applied to the input electrodes of vacuum tube 19 is given by the following equation:

$$e_1 = e_0 - e_1 g_m K - e_2 g_m K \quad (1)$$

where:

g_m = transconductances of the vacuum tubes 19 and 20, which in this analysis are assumed to be equal,

e_1 = the signal voltage applied between the cathode and grid of tube 19,

e_2 = the signal voltage applied between the cathode and grid of tube 20,

K = the total resistance of the resistors 29 and 33.

The magnitude of the signal voltage applied to the input electrodes of vacuum tube 20 is given by the following equation:

$$e_2 = -e_1 g_m K - e_1 g_m R - e_2 g_m K \quad (2)$$

The solution of Equations 1 and 2 when simplified, gives the following values for the voltages e_1 and e_2 :

$$e_1 = \frac{e_0 (1 + g_m K)}{1 + 2g_m K - g_m^2 R K} \quad (3)$$

$$e_2 = \frac{-e_0 (g_m R + g_m K)}{1 + 2g_m K - g_m^2 R K} \quad (4)$$

For balanced output, the voltages e_1 and e_2 should be equal; that is, the ratio of e_2 to e_1 should be unity. Thus, from Equations 3 and 4:

$$\frac{e_2}{e_1} = \frac{-(g_m R + g_m K)}{1 + g_m K} \quad (5)$$

which, for balanced output becomes:

$$\frac{e_2}{e_1} = \frac{-(g_m R + g_m K)}{1 + g_m K} = 1 \quad (5a)$$

Further, it is desired that the output of the amplifier shall be balanced over a wide range of values of the portion of the signal output of vacuum tube 19 which is applied to the input circuit of vacuum tube 20, that is, over a wide range of values of R. Thus, when $R=0$, Equation 5a for balanced output becomes:

$$-\frac{e_2}{e_1} = 1 = \frac{g_m K}{1 + g_m K} \quad (6)$$

It will be evident that Equation 6 is substantially satisfied if $g_m K$ is large compared to unity. If $g_m K$ has such value, Equation 5a simplifies into the following form:

$$-\frac{e_2}{e_1} = \frac{R + K}{K} = 1 \quad (7)$$

It will now be evident from Equation 7 that the amplifier has a substantially balanced signal output over a wide range of values of R if K is proportioned to be large compared to R.

From the above mathematical analysis of the Fig. 1 amplifier arrangement, it will be evident that the only conditions which must be satisfied to effect a substantially balanced output of the amplifier 16 over a wide range of values of R are; first, $g_m K$ must be large in comparison to unity and, second, K must be large compared to R.

These relationships are graphically shown by the curves of Fig. 3 in which Equation 5 is plotted with the ratio

$$\frac{e_2}{e_1}$$

as the axis of ordinates and $g_m R$ as the axis of abscissae for several values of $g_m K$. The broken-line curve A represents the ratio of the input voltages to the vacuum tubes 19 and 20 when the value of the resistor 33 is zero and it will be seen from this curve that the ratio of input voltages is unity, whereby the output of the amplifier is balanced, only at one value of R. However, when the resistor 33 has a value only sufficiently large that the product $g_m K$ equals 9, the ratio of the input voltage tubes 19 and 20 is represented by curve B and it will be evident that the output of the amplifier 16 is substantially balanced over a wide range of values of R. Curve C represents the condition when the value of the product $g_m K$ is very large compared to unity.

Adjustment of the tap 36 on the load resistor 21 provides an adjustment of the gain or repeating ratio of the amplifier 16. This will be evident from Equations 3 and 4 which simplify into the following forms when the resistor K is proportioned in the manner above described:

$$e_1 = \frac{e_0}{2 - g_m R} \quad (8)$$

$$e_2 = \frac{-e_0}{2 - g_m R} \quad (9)$$

It will be seen from Equations 8 and 9 that the voltage applied to the input electrodes of tubes 19 and 20 has a value one-half that of the input signal voltage e_0 when the resistor R has a value equal to 0, whereby the balanced input of the amplifier 16 is equal to the applied signal voltage e_0 . Similarly, the voltage applied to the input electrodes of tubes 19 and 20 is equal to the applied signal voltage e_0 when the value of $g_m R$ is equal to unity and the balanced input of the amplifier 16 is twice that of the applied signal voltage. When $g_m R$ approaches a value equal to 2, the amplifier becomes unstable and it is self-

oscillatory for values of $g_m R$ greater than 2. Thus, the repeating ratio or gain of the amplifier 16 may be controlled over a wide range of values by adjustment of the tap 36 on the load resistor 27.

This variation of gain of the amplifier 16 with adjustment of the tap 36 is graphically shown by the curves of Fig. 4 in which Equations 3 and 4 are plotted with the ratio of the input voltage applied to either the tube 19 or the tube 20 to the voltage applied to amplifier 16 as the axis of ordinates and the product $g_m R$ as the axis of abscissae. The solid-line curve D corresponds to Equation 3 and the broken-line curve E to Equation 4, the product $g_m K$ being given the value of 9 in each instance. It will be evident from these curves that the amplifier 16 is degenerative for values of $g_m R$ less than unity and regenerative for larger values of $g_m R$, the amplifier becoming self-oscillatory when the product $g_m R$ has a value equal to or greater than 2.

The inherent capacitance between the cathodes of tubes 19 and 20 and ground may, in certain instances, as when the frequency of the signal applied to amplifier 16 is relatively high, effect a slight unbalance of the output of the amplifier. The effect of such capacitance is avoided in the arrangement of Fig. 5 which is a circuit diagram representing a modified form of the invention essentially similar to that of Fig. 1, similar circuit elements being designated by similar reference numerals, except that an impedance comprising a resistor 33' is included in a circuit portion common to the output circuits of vacuum tubes 19 and 20. The signal developed across resistor 33' is effectively applied to the input circuit of vacuum tube 19 by a feedback path comprising a condenser 37 and a resistor 38 connected in series with grid leak 28. The resistor 33' is also effectively coupled into the input circuit of vacuum tube 20 by virtue of the connection of the control grid 22 of this tube to the tap 36 on the load resistor 27, which connection is effective to feed back to control grid 22 a portion of the potential across resistor 33', but a resistor 39 is additionally inserted between the control grid 22 and the condenser 35 in order that equal portions of the signal potential developed across the resistor 33' shall be applied to the grids 21 and 22 of the respective vacuum tubes 19 and 20. That is, the resistor 38 and the grid resistor 28 are effectively a voltage divider and comprise means for applying to the input circuit of tube 19 at least a predetermined portion of the signal voltage developed across the resistor 33'. The resistor 39 and the grid resistor 30 similarly are effectively a voltage divider and comprise means for applying at least the same predetermined portion of the signal voltage to the input circuit of vacuum tube 20. The screen grids of tubes 19 and 20 are energized from the battery 31 through at least a portion of the resistor 33', and preferably all thereof, and there is thus applied to the screen grids of these tubes a corresponding proportionate part of the signal potentials developed across this resistor. Consequently, the resistor 33' is effectively common to both the input and output circuits of tubes 19 and 20 and is also common to both the output and screen grid circuits thereof.

The operation of this modified form of the invention is essentially similar to that of Fig. 1 and will not be repeated. The desired balance of amplifier output is greatly improved in this arrangement by the action of the screen grids of

tubes 19 and 20. That is, a proportionate part, preferably all, of the signal potentials developed across the resistor 33' is applied to the screen electrodes or grids of tubes 19 and 20 which may in certain cases thus exert an even stronger balancing action than do the control grids 21 and 22 of these tubes which have applied thereto only a portion of the signal voltages developed across the resistor 33' by virtue of the voltage division effected by the resistors 38, 28 and 39, 30. It can be shown that the output of the Fig. 5 arrangement remains balanced over a wide range of values of the portion of the output of vacuum tube 19 which is applied to the input circuit of vacuum tube 20 when two conditions are fulfilled. These conditions are, first, that either or both $kK'g_m$ and $k'K'g'_m$ be proportioned to be large compared to unity, where k equals the ratio of the resistance of resistor 28 to the sum of the resistances of resistors 28 and 38 or, correspondingly, the ratio of the resistance of resistor 30 to the sum of the resistances of resistors 30 and 39, k' equals the proportionate part of the signal potential developed across the impedance 33' which is applied to the screen grids of tubes 19 and 20, and g'_m is the transconductances of the screen grid electrodes of the tubes 19 and 20; and, second, that the value of the resistor K' be large in comparison to the value of the resistor R , the parameters of these relations having the same significance as in Equations 1 to 9 except that K' represents the value of the resistor 33' alone and does not include the resistor 29 as did the resistor K in the analysis of the Figs. 1 and 2 arrangements.

While it has been stated that the impedance 33 in Fig. 1 and 33' in Fig. 5 comprises a resistor, it will be evident that other than resistive elements may be employed provided that the impedance has a primarily resistive component over the band of frequencies of the signal to be translated by the signal amplifier. The input and output circuits of the vacuum tubes of the amplifier may have a predominant reactive component without affecting the desired balanced operation.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A signal amplifier comprising, a pair of vacuum tubes each having input electrodes and an associated input circuit and output electrodes and an associated output circuit, said output circuits being connected to form a balanced amplifier output circuit, means for applying to the input circuit of one of said vacuum tubes a signal to be amplified, means for applying to the input circuit of the other said vacuum tubes a portion of the output of said one vacuum tube, and means for maintaining the output of said amplifier balanced over a range of values of said portion applied to the input circuit of said other vacuum tube comprising a relatively high impedance effectively common to all of said input and output circuits, the value of said impedance being such that the product of said value and the mutual conductance of one of said vacuum tubes is a number considerably greater than unity.

2. A signal amplifier comprising, a pair of vacuum tubes each having input electrodes and an associated input circuit and output electrodes and an associated output circuit, said vacuum tubes having a cathode circuit common to said output circuits and said output circuits being connected to form a balanced amplifier output circuit, means for applying to the input circuit of one of said vacuum tubes a signal to be amplified, means for applying to the input circuit of the other of said vacuum tubes a portion of the output of said one vacuum tube, and means for maintaining the output of said amplifier balanced over a range of values of said portion applied to the input circuit of said other vacuum tube comprising a relatively high impedance included in said common cathode circuit and effectively common to all of said input and output circuits, the value of said impedance being such that the product of said value and the mutual conductance of one of said vacuum tubes is a number considerably greater than unity.

3. A signal amplifier comprising, a pair of vacuum tubes each having input electrodes and an associated input circuit and output electrodes and an associated output circuit, said output circuits being connected to form a balanced amplifier output circuit, means for applying to the input circuit of one of said vacuum tubes a signal to be amplified, means for applying to the input circuit of the other of said vacuum tubes a portion of the output of said one vacuum tube, and means for maintaining the output of said amplifier balanced over a range of values of said portion applied to the input circuit of said other vacuum tube comprising a resistor of relatively large value effectively common to all of said input and output circuits, the value of said resistor being such that the product of said value and the mutual conductance of one of said vacuum tubes is a number considerably greater than unity.

4. A signal amplifier comprising, a pair of vacuum tubes each having input electrodes and an associated input circuit and output electrodes and an associated output circuit, said output circuits having a common circuit portion and being connected to form a balanced amplifier circuit, means for applying to the input circuit of one of said vacuum tubes a signal to be amplified, means for applying to the input circuit of the other of said vacuum tubes a portion of the output of said one vacuum tube, and means for maintaining the output of said amplifier balanced over a range of values of said portion applied to the input circuit of said other vacuum tube comprising a relatively high impedance included in said common circuit portion, the value of said impedance being such that the product of said value and the mutual conductance of one of said vacuum tubes is a number considerably greater than unity, and means for applying to each of said input circuits at least a portion of the signal potential developed across said impedance.

5. A signal amplifier comprising, a pair of vacuum tubes each having input electrodes and an associated input circuit and output electrodes and an associated output circuit, said output circuits having a common circuit portion and being connected to form a balanced amplifier circuit, means for applying to the input circuit of one of said vacuum tubes a signal to be amplified, means for applying to the input circuit

of the other of said vacuum tubes a portion of the output of said one vacuum tube, and means for maintaining the output of said amplifier balanced over a range of values of said portion applied to the input circuit of said other vacuum tube comprising a resistor of relatively large value included in said common circuit portion, the value of said resistor being such that the product of said value and the mutual conductance of one of said vacuum tubes is a number considerably greater than unity, and means for applying to each of said input circuits at least a portion of the signal potential developed across said resistor.

6. A signal amplifier comprising, a pair of vacuum tubes each having a screen electrode and having input electrodes and an associated input circuit and output electrodes and an associated output circuit, said output circuits having a common circuit portion and being connected to form a balanced amplifier circuit, means for applying to the input circuit of one of said vacuum tubes a signal to be amplified, means for applying to the input circuit of the other of said vacuum tubes a portion of the output of said one vacuum tube, and means for maintaining the output of said amplifier balanced over a range of values of said portion applied to the input circuit of said other vacuum tube comprising a relatively high impedance included in said common circuit portion, the value of said impedance being such that the product of said value and the mutual conductance of one of said vacuum tubes is a number considerably greater than unity, and means for applying to said screen electrodes at least a portion of the signal potentials developed across said impedance.

7. A signal amplifier comprising, a pair of vacuum tubes each having input electrodes and an associated input circuit and output electrodes and an associated output circuit, said output circuits being connected to form a balanced amplifier output circuit, means for applying to the input circuit of one of said vacuum tubes a signal to be amplified, means for applying to the input circuit of the other of said vacuum tubes a portion of the output of said one vacuum tube, means for maintaining the output of said amplifier balanced over a range of values of said portion applied to the input circuit of said other vacuum tube comprising a relatively high impedance effectively common to all of said input and output circuits, the value of said impedance being such that the product of said value and the mutual conductance of one of said vacuum tubes is a number considerably greater than unity, and means for selectively controlling the value of said portion applied to the input circuit of said other vacuum tube to control the repeating ratio of said amplifier.

8. A signal amplifier comprising, a pair of vacuum tubes each having input electrodes and an associated input circuit and output electrodes and an associated output circuit, said output circuits being connected to form a balanced amplifier output circuit, means for applying to the input circuit of one of said vacuum tubes a signal to be amplified, the output circuit of said one vacuum tube including a load resistor, means for applying to the input circuit of the other of said vacuum tubes a portion of the output of said one vacuum tube, means for maintaining the output of said amplifier balanced over a range of values of said portion applied to the input circuit of said other vacuum tube comprising a

relatively high impedance effectively common to all of said input and output circuits, the value of said impedance being such that the product of said value and the mutual conductance of one of said vacuum tubes is a number considerably greater than unity, and means including an adjustable tap on said load resistor for selectively controlling the value of said portion applied to the input circuit of said other vacuum tube to control the repeating ratio of said amplifier.

9. A signal amplifier comprising, a pair of vacuum tubes each having transconductance g_m and having input electrodes and an associated input circuit and output electrodes and an associated output circuit, said output circuits being connected to form a balanced amplifier output circuit, means for applying to the input circuit of one of said vacuum tubes a signal to be amplified, the output circuit of said one vacuum tube including a load impedance, means for coupling the input circuit of the other of said vacuum tubes to a selectable portion R of said load impedance, and means for maintaining the output of said amplifier balanced over a range of values of said portion R coupled to the input circuit of said other vacuum tube comprising a relatively high impedance K effectively common to all of said input and output circuits, the value of said impedance K being so proportioned that it is large compared to any value of R in said range of values and the product $g_m K$ is large compared to unity.

10. A signal amplifier comprising, a pair of vacuum tubes each having transconductance g_m and having input electrodes and an associated input circuit and output electrodes and an associated output circuit, said output circuits having a common circuit portion and being connected to form a balanced amplifier circuit, means for applying to the input circuit of one of said vacuum tubes a signal to be amplified, the output circuit of said one vacuum tube including a load impedance, means for coupling

the input circuit of the other of said vacuum tubes to a selectable portion R of said load impedance, and means for maintaining the output of said amplifier balanced over a range of values of said portion R coupled to the input circuit of said other vacuum tube comprising a relatively high impedance K included in said common circuit portion, and means for applying to the input circuits of both of said vacuum tubes a proportionate part k of the signal potential developed across said high impedance, the value of said impedance K being so proportioned that it is large compared to any value of R in said range of values and the product $g_m k K$ is large compared to unity.

11. A signal amplifier comprising, a pair of vacuum tubes each having a screen electrode having transconductance g'_m and having input electrodes and an associated input circuit and output electrodes and an associated output circuit, said output circuits having a common circuit portion and being connected to form a balanced amplifier circuit, means for applying to the input circuit of one of said vacuum tubes a signal to be amplified, the output circuit of said one vacuum tube including a load impedance, means for coupling the input circuit of the other of said vacuum tubes to a selectable portion R of said load impedance, and means for maintaining the output of said amplifier balanced over a range of values of said portion R coupled to the input circuit of said other vacuum tube comprising a relatively high impedance K included in said common circuit portion, and means for applying to the input circuit of the other of said vacuum tubes to a selectable portion R of said load impedance, and means for maintaining the output of said amplifier balanced over a range of values of said portion R coupled to the input circuit of said other vacuum tube comprising a relatively high impedance K included in said common circuit portion, and means for applying to said screen electrodes at least a portion k' of the signal potential developed across said high impedance, the value of said impedance K being so proportioned that it is large compared to any value of R in said range of values and the product $g'_m k' K$ is large compared to unity.

HAROLD M. LEWIS.
